(57) **CLAIM**

I claim the ornamental design for a video game controller, as shown and described.

DESCRIPTION

FIG. 1 is a top, back perspective view of a first embodiment of a video game controller, embodying my new design;

FIG. 2 is a top plan view thereof;

FIG. 3 is a bottom plan view thereof;

FIG. 4 is a front elevation view thereof;

FIG. 5 is a back elevation view thereof;

FIG. 6 is a side elevation view thereof;

FIG. 7 is an opposite side elevation view thereof;

FIG. 8 is a top, back perspective view of a second embodiment of a video game controller, embodying my new design;

FIG. 9 is a top plan view thereof;

FIG. 10 is a bottom plan view thereof;

FIG. 11 is a front elevation view thereof;

FIG. 12 is a back elevation view thereof;

FIG. 13 is a side elevation view thereof; and,

FIG. 14 is an opposite side elevation view thereof.

The broken lines represent the portions of the design that form no part of the claim.
